OSCILLATION GENERATOR AND
FREQUENCY MULTIPLIER

Alan P. Buffington, Philadelphia, Pa., assignor,
by mesne assignments, to Philco Corporation,
Philadelphia, Pa., a corporation of Pennsylvania

Application March 13, 1946, Serial No. 654,046

7 Claims. (Cl. 250—36)

1

This invention relates to improvements in frequency multipliers, and particularly to improvements in frequency multipliers of the type driven directly by an oscillator. The invention has been found to be applicable but is not limited to the combination of an oscillator and a frequency multiplier employing a single dual-purpose vacuum tube, as for example a double triode, which functions both as the oscillator and as the frequency multiplier.

It has long been conventional to use the superheterodyne principle in the amplification of received amplitude-modulated carrier wave signals, and it is equally conventional to use this principle in the amplification of received frequency-modulated signals. As is well known, superheterodyne receivers customarily employ a local oscillator for supplying the heterodyning frequency used by the mixer or converter tube in the process of converting the frequency of the carrier signals to an intermediate frequency which is more conveniently amplified.

Under recently prescribed regulations, the broadcast of frequency-modulated signals in the United States is assigned to the frequency band extending from 88 to 108 megacycles. This band is very high in comparison with the amplitude-modulation broadcast band which extends from 550 to 1600 kilocycles, and it is also substantially higher than both the AM short wave band (upper assigned limit approximately 22 megacycles) and the heretofore employed FM band (42 to 50 mc.).

The generation of local oscillations over the range of frequencies required for heterodyning with the recently assigned very high FM carrier band presents difficulties which were not present to any appreciable extent at the lower frequencies heretofore used. These difficulties may be reduced, but not altogether avoided, by the known expedient of employing an oscillator in combination with a frequency multiplier, the oscillator being operated at a sub-harmonic of the local frequency required for heterodyning, while the required high frequency oscillation is obtained from the output circuit of the frequency multiplier.

A frequency-modulation receiver employing an oscillator-multiplier in place of the more conventional fundamental-frequency oscillator is disclosed in the co-pending application of Milton L. Thompson, filed December 7, 1945, Serial No. 633,453, and assigned to the assignee of the present invention. While the arrangements therein disclosed are productive of very substantial improvements in the frequency stability of the locally generated oscillations, it has been found that

frequently the voltage output of the multiplier section of prior, tunable oscillator-multiplier circuits is neither large enough nor uniform enough for satisfactory performance of the receiver's frequency converter stage.

The output voltage obtainable from a frequency multiplier is known to be inversely proportional to the order of the selected harmonic. Consequently, in order to secure as high an output as possible, frequency multipliers are preferably employed to generate the second harmonic, rather than the third or higher harmonics, and as such are commonly referred to as frequency doublers. In the case of a superheterodyne FM receiver, assuming that an intermediate frequency of the order of 9 megacycles is to be employed and that the local oscillation frequency is to be on the low frequency side of the received signal, it will be necessary for the oscillator section of the oscillator-doubler to generate oscillations having frequencies tunable over the range extending from about 39 to 50 megacycles. The doubler section will accordingly deliver local oscillations whose frequencies are variable over the second harmonic range extending from 78 to 100 mc. The cause or causes of low and non-uniform doubler output voltage at these very high frequencies are difficult to determine. Among the factors involved is the fact that at high frequencies the inductive reactances of the leads between the various circuit components are appreciable in comparison to the reactance values of the circuit components themselves, and this is true even though the leads be kept as short as possible. Moreover, stray capacitances exist between the leads, the circuit elements, the tube electrodes, the chassis, etc., the values of which at these high frequencies are sufficient to affect seriously the operation of the apparatus. For these and other reasons, the operation of very high frequency apparatus is difficult to analyse accurately.

It will be understood by those skilled in the art that the local oscillation voltage introduced into the mixer or converter tube of a superheterodyne receiver is preferably held approximately constant over the frequency band; in general this voltage should be as large as possible without, of course, overloading the converter stage.

The reasons for the above are briefly as follows: The wave shape of the envelope of the beat or difference-frequency delivered by the mixer tube depends upon the relative amplitudes of the two component waves, that is, upon the relative amplitude of the local oscillator wave with respect to that of the incoming R.-F. carrier wave. For

linear detection, the amplitude of the local oscillation should be much greater than that of the R.-F. carrier wave. Where this is the case, the amplitude of the difference-frequency component of the mixer tube output is largely independent of the amplitude of the stronger local signal, and nearly proportional to the strength of the weaker incoming carrier signal. And the magnitude of the difference-frequency output is largest when the amplitude of the stronger component differs from the amplitude of the weaker signal by the greatest amount.

In a preferred form of the present invention, improvements are made in high frequency oscillator-multiplier circuits which effect a substantial increase in the amplitude of the multiplier output voltage and which also attain a substantial improvement in the uniformity of the amplitude over the frequency range.

In another form of the present invention, improvements are made in high frequency oscillator-multiplier circuits which cause the amplitude of the output voltage of the frequency multiplier to be more uniform in magnitude over the required frequency band without necessarily accomplishing increase in the amplitude.

It is an object of this invention to provide in combination a high frequency oscillator and a frequency multiplier, the frequency multiplier having improved uniformity of output voltage over the operating frequency range.

It is another object of this invention to provide a high frequency oscillator in combination with a frequency multiplier, where in the frequency multiplier has substantially increased output voltage, as well as improved uniformity of output voltage over the operating frequency range.

It is a more specific object of this invention to provide a high frequency oscillator-multiplier having external coupling arrangements between the output circuit of the frequency multiplier and the circuits of the oscillator whereby high frequency energy may be fed back from the multiplier to the oscillator to thereby achieve increased multiplier output and improved uniformity thereof over the operating frequency range.

These and other objects and advantages of the present invention, as well as the invention itself, will be best understood by reference to the following description and accompanying drawings wherein

Figure 1 is a schematic illustration of a preferred form of circuit organization for carrying my invention into effect; and

Figure 2 illustrates by means of a graph, the scope of the improvements which are realized from the invention.

Referring now to Figure 1, there is schematically illustrated a high frequency oscillator-frequency-multiplier in which the oscillator portion is tunable to a sub-harmonic of the desired local-oscillation frequency by means of the oscillator frequency-determining circuit 1 comprised of variable tuning capacitor 2, trimmer capacitor 3, and inductance coil or winding 4. The latter is inductively coupled to coil or winding 5 as shown. Vacuum tube V, which may be a commercial type 7F8 tube, is comprised of two triode sections, one of which functions as the oscillator. As shown in the figure, the external circuit connections of the oscillator include a plate circuit comprised of coupling capacitor 6, a part of inductance coil 5, conductor 25 (which, physically, is very short), and ground lug 8 of frequency-multiplier tank circuit 10, the return to the cathode 11 being

completed through the chassis. The use and function of ground lug 8 as a portion of the above plate circuit forms a part of the present invention and will be discussed more fully hereinafter.

5 The grid circuit of the oscillator portion of tube V includes grid capacitor 12, grid leak 13, parasitic suppressing resistor 14, a part of inductance coil 5, conductor 25, and the ground lug 8, the circuit to cathode 11 being completed through chassis.

The signal developed at grid 15 of the oscillator portion of tube V is applied directly to grid 16 of the second triode section of the tube. This second section of tube V functions as the frequency multiplier and is tunable to the desired harmonic of the oscillator frequency by frequency-determining circuit 10 which is comprised of variable tuning capacitor 17, trimmer capacitor 18 and inductance coil 9. For maximum multiplier output, circuit 10 is preferably tuned to the second harmonic of the frequency generated in the oscillator portion of the apparatus, and for convenience of operation tuning capacitors 2 and 17 may be ganged together by known mechanical means.

Assuming that the apparatus illustrated in Figure 1 is to function as an oscillator-doubler and is to be employed to supply the heterodyning frequency in a frequency-modulation receiver of the superheterodyne type, the operating frequency of the oscillator may be made variable by means of the tuning capacitor 2 over a range extending from about 39 to 50 megacycles. The frequency-doubler portion of the apparatus is, accordingly, tunable by means of the capacitor 17 over a range extending from about 78 to 100 megacycles, thus providing coverage of a band extending from about 87 to 109 megacycles when an intermediate frequency of 9 megacycles is employed. The tuned oscillator and doubler circuits should, of course, track accurately throughout their tunable ranges.

The output voltage of the multiplier may be taken from coil 9, as for example, from tap 19, 45 and may if desired be applied through conductor 20 directly to a control electrode of the converter tube of a superheterodyne receiver (not shown). If this is done, the most desirable tap point on coil 9 will be determined by the impedance of the converter tube into which the multiplier output voltage is injected.

Coupling capacitor 21 isolates the multiplier tank circuit from the high D.-C. voltage applied to the anode of the multiplier triode, while providing the necessary R.-F. coupling between said anode and said tank circuit. Resistor 22 and choke coil 23 are effective to isolate the tuned radio frequency circuits from B+. If desired, both of these isolating elements may be choke 60 coils, or both may be resistors.

In the conventional form of oscillator-multiplier, the low potential end of inductance coil 4 is either connected directly to the grounded sides of capacitors 2 and/or 3, or is grounded directly, as for example, to the chassis. Similarly, in the conventional circuit, the tapped connection 24 of coil 5 is either connected directly to cathode 11 or grounded directly, as to the chassis.

I have found, however, that the output voltage of a high frequency doubler or multiplier can be substantially increased, and in addition held relatively constant in amplitude over the required high frequency range, by connecting the low potential end of coil 4 and also the tapped connection 24 of coil 5 to a tapped point 26 near the low

potential end of coil 9. In Figure 1, these connections are made by way of conductor 25. The tapped connection 26 is preferably made very close to ground. In the actual construction of the particular high frequency oscillator-multiplier illustrated in Figure 1, the tapped connection 26 is made to the upper end of ground lug 8 which connects coil 9 to the chassis. It will be understood that at the high frequencies involved the inductance of lug 8 is appreciable and that lug 8 functions as a portion of coil 9. The physical dimensions of lug 8 were such that the ungrounded end thereof was approximately three-eighths of an inch removed from the chassis. I have found that the position of the tapped connection is most critical; for example, if tap 26 is moved to any appreciable extent either closer to or farther away from chassis (ground) than the end of lug 8, the improvements in the amplitude and uniformity of the multiplier output voltage rapidly diminish. Of course the optimum adjustment will vary in different arrangements, depending upon the physical size of the structures involved.

I have also observed that the direction of winding of coil 4 has a bearing upon the results achieved. With the winding in one direction, the optimum improvements in multiplier output voltage are obtained; if the winding be reversed the improvements may not be realized. Which direction of winding is productive of the most favorable results may be readily determined by trial.

Reference is now made to Figure 2 wherein curves representing the output voltage of the frequency multiplier are plotted against frequency, both for the conventional circuit and also for the novel circuit organization embodying the invention illustrated in Figure 1. Curve A of Figure 2 represents the output voltage characteristic of the frequency multiplier when the conventional form of circuit hereinbefore described is used. Curve B is the output voltage curve obtained when the novel arrangements of Figure 1 are employed. It will be observed that, with the exception of the extreme low-frequency end, the magnitude of the output voltage represented by curve B is much greater than that shown by curve A. It will be noted also that the voltage variations within the band 78 to 100 mc. are negligible in curve B as compared with those of curve A. Curve B therefore represents a very important improvement over the conditions shown in curve A.

The precise theory of operation of the improved circuit has not been definitely established. It will be appreciated by those skilled in the art that, at the very high frequencies here under consideration, stray inductances and stray capacitances existing throughout the circuits substantially affect the operation of the apparatus. These effects may be quite different at different frequencies in the operating range. For example, a particular, physically small portion of circuit may be series resonant at one frequency, and parallel resonant at a different frequency within the same operating band, and in consequence substantially affect the output voltage of the multiplier, or of the oscillator, or of both.

The circuit organization illustrated in Figure 1, which substantially improves the output voltage characteristics of the oscillator-multiplier, provides coupling means for feeding back high frequency energy from the output circuit of the multiplier to the plate and/or grid circuits of the oscillator, the phase relations apparently being

such that increased signal voltage on grid 16 of the multiplier is realized, thereby producing increased output.

If desired, only tap 24 of coil 5 may be connected to tap 26 of coil 9, the connection of the low potential end of coil 4 to tap 26 being omitted, and connection thereof made directly to the grounded sides of capacitors 2 and/or 3, or to chassis (ground) in the conventional manner.

10 Or, the above connections may be reversed, that is, the low potential end of coil 4 may be connected to tap 26 of coil 9, tap 24 of coil 5 being connected in the conventional manner directly to chassis (ground) or directly to cathode 11.

15 I found that if the preferred circuit illustrated in Figure 1 is modified in either of the above manners, the output voltage characteristic of the multiplier is appreciably improved over that of the conventional circuit insofar as uniformity of output over the frequency band is concerned; but substantially increased amplitude of output is not realized.

20 I have described and illustrated my invention by means of an oscillator-multiplier which uses a single dual purpose vacuum tube, but it will be understood that the invention is also applicable to the combination of an oscillator and frequency multiplier in which separate vacuum tube envelopes are employed. Moreover, the invention is not limited to the particular form of oscillator circuit shown in the illustration; any of the oscillator circuits known to be suitable for the generation of high frequency oscillations, of the order and for the purposes here involved, may be employed.

25 Having described my invention in a preferred form, but intending to be limited only by the scope of the claims, I claim:

30 1. In combination, a high frequency oscillator comprising a tube having cathode, plate and grid electrodes, said oscillator including a tunable frequency-determining network and plate-cathode and grid-cathode circuits, a frequency multiplier having an output circuit tunable to a harmonic of the oscillator frequency, means for applying the oscillator output to the multiplier, and means for applying a portion of the output of said multiplier to the grid-cathode circuit of the oscillator.

35 2. In combination, a high frequency oscillator comprising a tube having cathode, plate and grid electrodes, said oscillator including a tunable frequency-determining network and plate-cathode and grid-cathode circuits, a frequency multiplier having an output circuit tunable to a harmonic of the oscillator frequency, means for applying the oscillator output to the multiplier, and means for applying a portion of the output of said multiplier to the plate-cathode and grid-cathode circuits of the oscillator.

40 3. In combination, a high frequency oscillator comprising a tube having cathode, plate and grid electrodes, said oscillator including a tunable frequency-determining network inductively coupled to the grid-cathode and plate-cathode circuits of said oscillator, a frequency multiplier having an output network tunable to a harmonic of the oscillator frequency, means for applying the oscillator output to the multiplier, and means for applying a portion of the multiplier output to the frequency-determining network of the oscillator.

45 4. In a high frequency oscillator-multiplier having an oscillator section which includes a tube having cathode, plate and grid electrodes

50 75

and a tunable frequency-determining network inductively coupled to the grid-cathode and plate-cathode circuits of said oscillator and having a multiplier section which includes an output network tunable to a harmonic of the oscillator frequency; means for applying a portion of the multiplier output to the grid-cathode circuit of the oscillator and to the oscillator's frequency-determining network, said means comprising a connection from the multiplier output network to the oscillator's frequency-determining network and grid-cathode circuit.

5. An oscillator-multiplier including two triodes in a single vacuum tube envelope, the multiplier portion comprising one of said triodes and a frequency-determining output circuit including an inductance, the oscillator portion comprising the other of said triodes and plate-cathode and grid-cathode circuits including a tunable frequency-determining network, said grid-cathode circuit including a tapped portion of said multiplier output inductance, said tapped portion comprising a portion near the low potential end of said multiplier inductance.

6. A high frequency oscillator-doubler including two triodes in a single vacuum tube envelope, the doubler portion comprising one of said triodes and a frequency-determining output circuit including an inductance, the oscillator portion comprising the other of said triodes and plate-

5 cathode and grid-cathode circuits including a tunable frequency-determining network, said grid-cathode circuit including a tapped portion of said doubler output inductance, said tapped portion being a portion of the low potential end of said doubler inductance.

7. An oscillator-doubler including a double triode vacuum tube, said doubler portion comprising one of said triodes and a tunable frequency-determining output circuit including an inductance coil, said oscillator portion comprising the other of said triodes, a plate-cathode circuit, a grid-cathode circuit, and a tunable frequency-determining network inductively coupled to said plate-cathode and grid-cathode circuits, said grid-cathode circuit including a tapped portion of said doubler output inductance coil, said tapped portion comprising a portion of the low potential end of said doubler output inductance coil.
